CLAIM

We claim the ornamental design for a carton with food containers, as shown and described.

DESCRIPTION

FIG. 1 is a top perspective view of a carton with food containers.

FIG. 2 is a front view of the carton shown in FIG. 1.

FIG. 3 is a rear view of the carton shown in FIG. 1.

FIG. 4 is a right side view of the carton shown in FIG. 1.

FIG. 5 is a left side view of the carton shown in FIG. 1.

FIG. 6 is a top view of the carton shown in FIG. 1; and,

FIG. 7 is a bottom view of the carton shown in FIG. 1.

The broken lines having equal segments represent portions of the article that form no part of the claimed design.

1 Claim, 7 Drawing Sheets(56)
